UNITED STATES PATENT OFFICE.

WILLIAM HINCHLIFFE, OF NASHVILLE, TENNESSEE, ASSIGNOR OF ONE-HALF TO GEORGE DRAPER & SONS, OF HOPEDALE, MASS.

SPINDLE-SUPPORT FOR SPINNING-MACHINES.

SPECIFICATION forming part of Letters Patent No. 361,359, dated April 19, 1887.

Application filed November 15, 1886. Serial No. 218,880. (No model.)

To all whom it may concern:

Be it known that I, WILLIAM HINCHLIFFE, of Nashville, county of Davidson, and State of Tennessee, have invented an Improvement in Spindle-Supports for Spinning - Machines, of which the following description, in connection with the accompanying drawing, is a specification, like letters on the drawing representing like parts.

10 This invention has for its object the production of an improved spindle-support having provision to permit the lower end of the spindle to move as the spindle seeks to find its true center under an unbalanced load.

15 In this invention the bolster-case is provided with a bolster, which is held rigidly therein, the bolster being open at its lower end, and below the bolster is a loosely-held step, which is restrained from rotation with the spindle, 20 the said step, as herein shown, being mounted on a vertical pin or stud.

My invention is shown as embodied in a sleeve-whirl spindle.

With a spindle such as herein shown the 25 employment of elastic packing, so frequently used between the bolster and bolster-case, is not necessary. One part of the bolster for a portion of its length fits the bolster - case snugly, while another part of the bolster, 30 which fits the spindle more closely, is of such diameter externally that it rests within, but does not touch, the inner walls of the bolster-case, the absence of contact between the bolster and bolster-case lessening the transmission of jar.

35 The drawing shows a sleeve-whirl, a bolster, a step, a bolster-rail, and a nut in section, the spindle and pin for supporting the step being in elevation.

40 The bolster-rail A receives within it the bolster-case B, extended below the rail for, as herein shown, a considerable distance, and being held in place on the rail by a nut, B'. The bolster a, made as a tube, is herein shown 45 reduced in diameter from the shoulder 2 to its upper end, the lower end of the bolster, of larger diameter, fitting the bolster-case rigidly, the portion of the bolster above the

shoulder 2 being enough smaller in diameter externally to normally stand in the bolster-case without touching the inner wall thereof. 50

The downwardly-extended lower end of the bolster-case has, as herein shown, screwed into it a nut, b, which serves to hold a stud, b', herein represented as tapering, the said 55 stud supporting the spindle-step C, the latter being of considerably smaller diameter externally than the interior bore of the bolster-case, so that the step loosely fitted on the stud b' has a freedom of motion or vibration 60 laterally in substantially every direction within the bolster-case below the bolster, the step so supported receiving within it the pintle 3 of the spindle D, the step thus held being adapted to move as the lower end of the spindle, 65 in seeking its true center of motion under an unbalanced load, moves within the bolster-case.

The step C is prevented from rotation in the bolster-case by means of a screw pin or 70 projection, e, extended through the bolster-case into the step. The sleeve-whirl is extended down about the upper end of the bolster-case.

In this as in other spindle-bearings there 75 is a suitable space between the spindle and bolster for oil.

I do not claim a spindle supported directly upon a flexible or laterally-yielding pin, the spindle running in a bolster mounted loosely 80 in a bolster-case. By holding the bolster rigidly the spindle is more accurately centered with relation to the ring, and is also held more nearly perpendicular in rotation.

I claim—

1. The combination, with the bolster-case and bolster held rigidly therein, of a pin or step support and loose step free to move in any direction thereon with the lower end of the spindle as the latter centers itself to an 90 unbalanced load, substantially as described.

2. The combination, with the bolster-case and bolster, held rigidly therein at one end, of a loose step free to move in any direction with the lower end of the spindle as the latter centers itself to an unbalanced load, and a 95

pin or projection to prevent the rotation of the step with the spindle, substantially as described.

3. The bolster-case, the bolster held rigidly therein, and the pin b' , combined with the step mounted loosely on the said pin and having a recess to receive the foot of the spindle, all substantially as described.

In testimony whereof I have signed my name to this specification in the presence of two subscribing witnesses.

WM. HINCHLIFFE.
